UNITED STATES PATENT OFFICE.

JOSEPH SYLVAN, OF CHICAGO, ILLINOIS.

WINDOW CONSTRUCTION.

1,379,061.

Specification of Letters Patent. Patented May 24, 1921.

Application filed July 19, 1920. Serial No. 397,390.

To all whom it may concern:

Be it known that I, JOSEPH SYLVAN, a citizen of the United States, and a resident of Chicago, in the county of Cook and State of Illinois, have invented certain new and useful Improvements in Window Construction; and I do hereby declare that the following is a full, clear, and exact description thereof, reference being had to the accompanying drawings, and to the letters of reference marked thereon, which form a part of this specification.

This invention relates to improvements in window construction and consists of the matters hereinafter described and more particularly pointed out in the appended claims.

One of the objects of the present invention is to provide a window construction, wherein the window sash are not only capable of a vertical movement in the window frame, but are also capable of being swung vertically inwardly into the room about their bottom ends as a pivot, for the purpose of either cleaning the window panes, or for the purpose of using the sash to deflect the incoming air, upwardly toward the ceiling of the room.

This object, as well as others, together with the several advantages thereof will more fully appear as I proceed with my specification.

In the drawings:—

Figure 1 is a vertical section through a window construction embodying my invention.

Fig. 2 is a similar view with the window sash in a changed relation.

Fig. 3 is a view in elevation of a window construction embodying my invention as viewed from the inside of a room.

Fig. 4 is a detail horizontal section, on an enlarged scale, taken on the line 4—4 of Fig. 1.

Fig. 5 is an enlarged detail view of parts shown in the upper right hand corner of Fig. 4.

Fig. 6 is a perspective view of the upper window sash with parts broken away to more clearly show the construction thereof.

Figs. 7, 8 and 9 are detail perspective views, on an enlarged scale, of parts of the window construction which will be more particularly referred to later.

Referring now in detail to that embodiment of the invention illustrated in the accompanying drawings: 10 indicates a wooden

window frame and 11 and 12 indicate the lower and upper windows capable of a vertical movement in said frame. The sash of the windows in this instance are shown as 60 made of sheet metal.

The window frame has the usual upright side grooves 13 and 14 defined by inner, intermediate and outer strips 15, 16 and 17 which extend from the stepped sill 18 to the 65 lintel or member 19 at the top of the frame, the lintel having downwardly facing horizontal grooves 20 and 21, which register with the grooves 13 and 14. Preferably, but not necessarily so, each upright groove 70 13 and 14 is shod or lined with a sheet metal channel strip 22, a part of which is shown in perspective in Fig. 7, the channels being attached in any suitable manner.

Secured to the face of each channel along 75 its vertical median line and extending from the bottom almost to the top thereof, is a rail 23, shown in detail in Fig. 8. This rail is preferably made of a narrow strip of band iron 24 to the outer face of which is secured 80 a wider strip of sheet metal 25, the margins of which are bent inwardly of the strip so that the edges of the bent-in margins and the edges of the band iron engage each other to provide lateral guide flanges 26, which 85 are spaced from both the web and flanges of said channel 22, when said rails are in place in said channels.

Engaging with the rails 23 and extending into the channels 22 so as to be capable of 90 a vertical guided sliding movement in said channel grooves, are channeled runner strips 27 (see Fig. 9) which are of a height corresponding to the height of each window 11 and 12, and of a width sufficient to project 95 inwardly toward each other a short distance beyond the surfaces of the strips 15—16 and 17 of the window frame. Each runner strip comprises front and rear side webs 28—29 which terminate in bent-over, spaced 100 hook flanges 30—30 at the outer ends, an inner web 31, and a parallel hook flange 32 which leads off from the web 29 and extends toward the web 28 and is spaced from the web 31, to provide an inwardly opening 10 groove 33, between said web and hook flange 32. This runner strip fits within the channel 22 and its spaced, hooked flanges 30 bear between the web of said channel 22 and the flanges 26 of the rail 23, as shown in Figs. 11 4 and 5. In each inner web 28 of each runner strip is provided one or more, vertically

spaced depressions or notches 34, the purpose of which will hereinafter appear.

As before mentioned, the sash of each window are made of tubular sheet metal.

- 5 35 indicates the sash of the lower or bottom window and 36 indicates the sash of the upper or top window (see Figs. 1 and 6) and 37 indicates the glass panes thereof, said sash being of a thickness equal to the 10 width of the runners 27. Each window sash includes top, bottom and side frame members 38, 39 and 40 respectively, of rectangular, hollow, tubular formation, which are formed on their inner surfaces to provide grooves to receive the associated panes 37. In the inner surface of the top member 38 of the bottom sash and in the inner surface of the bottom member 39 of the top sash is a depression 41 to 15 provide a hand hold for the purpose of operating either window. The bottom member of each sash is rounded along its inner front margin, as shown in Figs. 1 and 2, and the bottom member 39 of the top sash 20 has an inwardly extending, bent-over flange 42, which bridges the space between the sash 35—36 defined by the intermediate strips 16 of the window frame 10. Said flange 42 terminates at its ends short of the planes 25 of the outer surfaces of the side members 40 of the top sash as shown in Figs. 4 and 6. When the top and bottom sash are in the closed position shown in Fig. 1, the top surface of the flange 42 of the upper window sash is flush with the top surface of the top member 38 of the bottom window sash and said flange and top surface of the bottom sash having coacting locking devices 33 of any usual kind to lock said sash together in the closed position. Fixed to the 30 intermediate strips 16 of the window sash at a point between the bottom member of the top sash and the top member of the bottom sash, are blocks 44 (see Figs. 1 and 4) 35 which close the spaces at the ends of the flange 42 of the top window sash against the entrance of wind or rain, when said sash are in their normal closed position.
- The side members 40 of each sash which, 40 as before mentioned, are of a thickness equal to the width of the runner 27, are formed to provide outwardly facing bent-over flanges 45 and spaces 46 between said flanges and a part of the outer web of said sash. When 45 the sash are in their normal, upright position, the flanges and spaces of said sash and runners 27 inter-engage with each other, as shown in Fig. 5, the friction of said parts being sufficient to hold them in 50 the plane of each other against accidental displacement. The side members 40 of each sash are pivotally connected on their median line, at the bottom of the sash, to the bottom ends of the associated runners 27, by 55 means of studs 47. Each stud 47 also serves
- as a convenient point of attachment for one end of the sash chain or cords 48, which are free to extend up through the top end of the runner and to pass over pulleys 49 at the top ends of the grooves 13—14, the 70 other ends of the chains or cords being connected to sash weights (not shown) in the usual way provided therefor in the window frame.
- 50 indicates swinging levers which are 75 pivoted near their top ends, at predetermined points on the inner strips 15, on pins 51. Said levers carry at their bottom end, rollers 52, which extend inwardly toward each other, a short distance beyond the 80 flanges 32 of the runner strips 27 as shown in Figs. 1 and 4. 50^a indicates similar but shorter levers which are pivoted near their top ends on pins 51^a on the intermediate strips 16 of the frame at a point preferably 85 just above the rollers 52 of the levers 50. The levers 50^a carry similar rollers 52^a at their bottom ends.
- The operation and use of the improved window construction is as follows: Assume 90 that the sash are in the normally closed positions shown in Fig. 1 and it is desired to open the lower window sash either for the purpose of deflecting the incoming air upwardly into the room, or for the purpose 95 of washing the outer surface of the window pane thereof. The coacting locking devices 43, between the top of the bottom window sash and the bottom flange 42 of the top window sash are first unlocked. The 100 top end of the bottom window sash is grasped and pulled inwardly, whereupon a separation will occur between the hook flanges 45 of the bottom window sash and the associated flanges 32 on the runners, the 105 window swinging inwardly and downward about the pivot pins 47, before mentioned, as an axis. In this swinging movement, the side members 40 of the sash will engage and pick up the rollers 52 of the levers 50, causing 110 said levers to swing with the rollers which roll along the inner margins of the side members of the sash until the limit of said opening movement is reached, which occurs when the sash and levers extend at 115 about a right angle to each other. As the bottom end of levers 50 move inwardly, the shorter top ends move outwardly and enter and engage in the depressions 34 in the 120 runners 27 to lock said runners against movement, under the action of the sash cords or chains and associated weights. Thus even though the levers 50 assume some of the weight of the window sash 35, when it has been swung inwardly and has thus 125 removed its weight from the sash cords the sash weights cannot act to accidentally raise or lift the sash and runners while the sash is in its open position. Thus the incoming air strikes the window pane and is deflected 130

upwardly into the room and the window pane is in convenient position for cleaning without the necessity of standing or sitting on the window sill and exposing the person cleaning the same to the danger of falling from said sill. It is apparent that, if it is desired to have the sash swing into a more nearly horizontal position than that shown in Fig. 1, it is only necessary to raise the window sash and runners vertically in the associated grooves and then swing the sash inwardly about its pivotal connection with its runners until the sash again engages the rollers 52, the relative positions of the pivot pins 47 with reference to pivot 51 of the levers, determining the angular position into which the sash may be swung. Of course the top ends of the levers 50, will engage in notches 34 in the runners which are arranged therein to correspond to the position it is desired to open the windows.

To close or move the window sash back to its vertical position, it is only necessary to push the top member of the sash frame upwardly and outwardly when the coating flanges on the runners and sash will frictionally hold the window sash in this vertical position, the levers 50 swinging back by gravity to their normal, vertical positions.

30 To swing the top window sash into the open position shown in Fig. 2, it is first necessary to raise the lower window sash and runners and then pull down on the top window sash and runners, the flange 42 on the bottom member of the top sash being free to pass the rollers 52^a on the levers 50^a on the intermediate frame strips 16, by reason of said flange terminating short of the sides of the sash. Thereafter said top sash may be 40 swung about its pivot with its runners in the same manner as described in connection with the bottom window sash.

My improved window construction possesses many advantages—the sash may be 45 swung inwardly about the bottom ends as a pivot so that the sash may be used to deflect the incoming air upwardly toward the ceiling of the room. Thus ample ventilation may be provided without the disadvantage 50 of having the incoming air blow directly into the room. They may also be cleaned from within the room. The improved construction may be readily applied to old window frames, as well as to new window 55 frames. When said sash are in their closed position, as shown in Fig. 1, they are air tight to keep out drafts of air and will not rattle. Thus the window is equally adapted for use in dwellings, as well as in office and 60 shop buildings.

While in describing my invention, I have referred to certain details of mechanical construction and arrangement of parts, I do not wish to be limited thereto, except as may 65 be pointed out in the appended claims.

I claim as my invention:

1. A window construction comprising, in combination with a window frame having upright side grooves, runners slideable in said grooves, a window sash pivoted at one end to said runners, and capable of a swinging opening movement with respect thereto, window weight cords connected to said runners, and means limiting the swinging opening movement of the sash with respect to said runners, said means acting to lock said runners against the action of the window weight cords as the window sash swings into its open position. 70

2. A window construction comprising, in combination with a window frame having upright side grooves, runners slideable in said grooves, a window sash pivoted at one end to said runners, and capable of a swinging opening movement with respect thereto, window weight cords connected to said runners, and means on the window frame limiting the swinging opening movement of the sash with respect to the runners, said means acting to lock said runners against the action of the window weight cords as the window sash swings into its open position. 85

3. A window construction, comprising, in combination with a window frame having upright side grooves, runners slideable in said grooves, a window sash pivoted at one end to said runners, and capable of a swinging opening movement with respect thereto, window weight cords connected to said sash and runners where they are pivoted together, swinging levers on the window sash, and rollers on the bottom end of said levers, said rollers being adapted to be engaged by and swing inwardly with said sash to limit its swinging opening movement, while the top ends of said levers swing outwardly to engage the runners, to lock them against the action of the window weight cords as said sash swings into its open position. 95

4. A window construction comprising, in combination with a window frame having upright side grooves, runners slideable in said grooves, a window sash pivoted at its bottom end to said runners, and capable of a swinging opening movement with respect thereto, inter-engaging parts on said runners and sash to hold them in the plane of each other, window weight cords connected to said runners, and means limiting the swinging opening movement of the sash with respect to the runners, said means acting to lock the runners against the action of the window weight cords as the sash swings into its open position. 115 120

5. A window construction comprising, in combination with a window frame having upright side grooves, runners slideable in said grooves, each runner including an upright, inwardly facing hook flange spaced from the body of said runner, window 125 130

- weight cords connected to said runners, a
window sash pivoted at its bottom end to
said runners, the side members of said sash
having upright, outwardly facing flanges
5 spaced from the body of said side members
of the sash, the flanges of said sash and runners
being adapted to engage each other to hold
said sash and runners in the plane of each other, and means limiting the open-
10 ing, swinging movement of the sash with reference to the runners, said means acting to lock the runners against the action of the window weight cords as the sash swings into its open position.
- 15 6. A window construction comprising, in combination with a window frame having upright side grooves defined by inner, outer and intermediate upright strips, a runner
20 slideable in each groove, top and bottom window sash pivotally connected at their bottom ends to said runners and capable of an inward swinging movement with respect to said runners, window weight cords asso-
ciated with each sash, levers, including rollers, pivoted to the inner and intermediate strips to limit the inward swinging movement of the sash, said top sash having an inwardly extending flange normally bridging the space between said sash in the plane of the intermediate strip, said flange terminating short of the sides of the top sash to permit said top sash to pass its associated levers and rollers in its downward movement, and filler blocks secured to said intermediate strip to close the space at the ends of the flange of the top sash when said sash is in its normal, closed position.
- In testimony that I claim the foregoing as my invention, I affix my signature in the presence of two witnesses, this 7th day of 40 July A. D. 1920.

JOSEPH SYLVAN.
